J. E. BUSBY

ADJUSTABLE RAIL BREAKING CLAMP

Filed May 26, 1923

UNITED STATES PATENT OFFICE.

JUNIUS E. BUSBY, OF HAZARD, KENTUCKY, ASSIGNOR OF ONE-HALF TO BENTON R. COOPER, OF COVINGTON, KENTUCKY.

ADJUSTABLE RAIL-BREAKING CLAMP.

Application filed May 26, 1923. Serial No. 641,680.

To all whom it may concern:

Be it known that I, JUNIUS E. BUSBY, a citizen of the United States, residing at Hazard, in the county of Perry and State 5 of Kentucky, have invented certain new and useful Improvements in Adjustable Rail-Breaking Clamps, of which the following is a specification, reference being had to the accompanying drawings.

10 This invention relates to means for breaking or bending railroad rails, and particularly to certain improvements in the rail breaking clamp disclosed in my application Serial No. 569,232, filed June 19, 1922.

15 In railroad construction, rail sections of different lengths are used and these rail sections are usually made by bending and breaking standard railroad rails.

The general object of my invention is to 20 provide a clamp for this purpose which is adapted to engage with and be bound tightly upon a track rail, and which is also formed to engage with and bind tightly upon a rail section which is to be bent or broken so that 25 one portion of the rail section may be held rigidly while the other portion is bent or while it is being cut.

A further object is to provide a device of 30 this character which is adjustable to different sized supporting or track rails.

A still further object is to provide a device of this character in which the filler blocks are held positively in place against any shifting movement whereby to prevent 35 the rail that is to be broken from slipping endwise when the rail is sprung around, especially when breaking off five or six inches of the rail.

Another object is to provide a chisel holding 40 attachment mounted upon the breaker, which chisel holding attachment is adjustable so as to permit the chisel to be set at any desired angle, the chisel holding attachment furthermore doing away with the 45 necessity of a workman holding the chisel while cutting the rail.

Still another object is to provide a chisel holding attachment which is entirely detachable from the breaker and which may 50 be applied at either end of the breaker.

Other objects will appear in the course of the following description.

My invention is illustrated in the accompanying drawings, wherein:—

55 Figure 1 is a perspective view of my im-

proved rail breaking clamp in applied position;

Figure 2 is a sectional view through the supporting rail and the rail which is to be broken, showing my rail breaking clamp 60 thereon;

Figure 3 is a fragmentary plan view of the rail breaking clamp showing the socket for the chisel;

Figure 4 is a perspective view of one of 65 the clamping members 16 detached;

Figure 5 is a perspective view of the U-shaped shim 17;

Figure 6 is a perspective view of one of 70 the filler blocks 21.

Referring to these drawings, 10 designates the body of the clamp, which is of any desired length but which is of sufficient length so as to secure a firm engagement with the supporting rail and with the rail to be bent. 75 This body 10 is formed on its under face with a recess 11 in its middle adapted to engage over the head *c* of a rail *C*. The under face of the clamp on each side of the recess extends upward and outward, as at 12, 80 and depending from the under face of the clamp are the oppositely disposed pairs of parallel lugs 13 which are apertured at 14 for the passage of a pin 15. Clamping blocks 16 are adapted to be disposed between 85 these pairs of ears 13 and to be forced against the web of the rail beneath the head thereof and over the base flange thereof, these clamping blocks being apertured for the passage of the pin 15, and obviously when 90 these clamping blocks are forced into place and the pins 15 have locked the clamping blocks in place, the body 10 of the clamp will be rigidly engaged with the rail *C*. Furthermore, the upper faces of the block 16 are 95 downwardly and inwardly beveled or inclined when the blocks are in place so that these blocks will bear against the somewhat beveled under face of the head of the rail and will act to draw the body 10 downward 100 upon the head of the rail and tightly clamp it in position.

The recess 11 is made large enough so as to receive the head of the largest possible rail or a rail the head of which has been enlarged by traffic and in order to fit smaller rails I provide the U-shaped shims 17 which fit over the head of the rail and fill up the space between the head of the rail and the wall of the recess 11. By the use of these 110

shims the body 10 may be applied to rails of various sizes and to rails which have been damaged or deformed. By removing the pins 15 it is an easy matter to slip the clamps 16 outward so as to permit the body to be slid along the rail C to any desired position or to be entirely removed from the rail. When these clamps 16, however, are in engagement with the rail C, the body 10 is rigidly held upon the rail from any longitudinal movement or from any tilting movement.

The body 10 at its ends has the upwardly extending opposed jaws 18 which have the same length as the body and which have overhanging portions 19 which are adapted to overhang the base *d* of the rail D which is to be bent or broken. The overhanging portions 19 are longitudinally grooved upon their under faces, as at 20, and disposed between the base flange *d* of the rail and these overhanging portions 19 are the fillers 21. These are angular in form so as to extend down over the side edges of the flange *d* and also along the upper face of the flange, and these fillers are provided with longitudinally extending ribs 22, fitting within the grooves 20. The fillers 21 are somewhat wedge-shaped so that when they are driven in they will tightly clamp against the base *d* of the rail D and lock the rail firmly in place between the jaws 18. Set screws 23 pass through apertures in the overhanging portions 19 of the jaws and pass through apertures 24 in the fillers. These set screws engage the base of the rail D to prevent the rail D which is to be broken from slipping endwise when the rail is sprung around. This slipping is especially liable to occur when breaking off five or six inches of the rail. Furthermore these set screws prevent the fillers from being lost when the device is shipped from one point to another. It is to be understood that the fillers will be made in proper proportions to fit different sized rails, or in other words a pair of fillers will be made for each size of rail and thus this breaker will be adjustable for all sizes of rail.

The outer faces of the body 10 and conjoined jaws 18 are angular and adapted to fit upon these angular faces is an angular base plate 25 apertured for the passage of a set screw 26, the body 10 being formed with a screw-threaded aperture on each of its lateral faces for engagement with this set screw. Preferably these apertures will be located at the middle of the body 10.

Attached to the base 25 at one end is an upwardly extending wall or flange 27 having an arcuate slit 28, and coacting with this plate or wall 27 and disposed against the outer face thereof is a chisel socket 29 open at its outer and inner ends and which is provided with a stud bolt 30 carrying a wing

nut 31. Adapted to be disposed within this socket is the chisel 32 which may be adjusted to engage the edge of the flange *d* and may be driven against this flange by means of a maul or other suitable instrument so as to fit a kerf or notch in the flange which will sufficiently weaken the flange to permit the rail to be bent and eventually broken. The arcuate slot 28 is curved on an arc whose center is approximately the point of engagement of the chisel with the flange *d* and thus it will be obvious that the chisel may be held by this socket or holder 29 in any desired angular position where it is most convenient to be struck by the workman. This socket 29 does away with the necessity of a workman holding the chisel while another workman drives the chisel inward against the flange.

It will be noted that the body 10 has the extremities of its jaws 18 and 19 spaced sufficiently from each other so as to permit the rail D to be slipped into place laterally, or the rail D may be slipped longitudinally into place between the jaws. After the rail D is in place the fillers 21 are driven inward and clamped tightly upon the rail by the set screws 23 which, as before stated, engage the base *d* of the rail so as to hold this rail D very firmly. The chisel is then used to cut a notch in the flange *d* and force is applied to curve or bend the rail at a point right opposite the kerf, this operation being shown in Figure 1. As the rail is bent the chisel is driven further and further in until eventually the rail may be broken off. Of course, it is obvious that this may be used simply as a clamp for angling or bending the rail without the necessity of using the chisel if desired. The chisel socket may be shifted into any desired angular position and then locked by means of the wing nut 31. If it be desired to remove the breaker from the rail D, it is only necessary to pull out the pins 15 which are normally held in place by cotter keys or any other suitable devices of this character. The breaker may be then shifted longitudinally along the rail D or lifted bodily off therefrom.

The U-shaped shim 17 adapts this breaker for use on rails with narrow balls or heads or worn rails or curved worn rails and rails which are otherwise deformed, so that thus the breaker may be applied at any place along a track. The chisel holding attachment is made detachable from the breaker so that should it become broken another one may be applied. The chisel holder is made adjustable and set at any angle desired and this chisel attachment can be disposed at either end of the breaker for the reason that the cap screw 26 is disposed at the middle of the body 10.

One of the improvements in the present mechanism over that disclosed in my appli-

cation, Serial No. 569,232, heretofore referred to, is that with this construction the clamps 16 are engaged with the rail C entirely above the base thereof so that there is no necessity of digging out ballast between the ties in order to dispose the clamp upon a rail. It is also to be noted that the clamp 16 is held in place by a pin 15 passing through a round hole instead of the clamp being held by a pin passing through an elongated hole, which is liable to let the clamp slip. Furthermore, the member 10 is clamped upon the rail by two set screws as well as by the fillers 21 so that there is no chance for the rail to slip endwise when the rail D is being bent or cut or otherwise acted upon. Furthermore, the fillers will not be lost.

I claim:—

1. A rail breaker comprising a body adapted to rest upon a supporting rail and be clamped thereon, the body being formed with opposed overhanging jaws, means for clamping a rail between said jaws, and a chisel holder mounted upon the body and adjustable in a vertical plane around a center approximately coincident with the corner of the flange of the last named rail.

2. A rail breaker comprising a body adapted to rest upon and be clamped on a supporting rail and having means for engaging and clamping upon the base of a rail to be broken, a chisel socket, and means mounted upon the body for adjustably supporting said socket at either end of the body.

3. A rail breaker comprising a body adapted to rest upon and be clamped on a supporting rail and having means for engaging and clamping upon the base of a rail to be broken, a chisel socket, and means mounted upon the body for adjustably supporting said socket at either end of the body and including an outwardly projecting member having an arcuate slot, the socket having an adjusting bolt passing through said slot and adjustable therein, the slot being disposed approximately concentric to the edge of the base flange of the second named rail.

4. A rail breaker comprising a body formed with a longitudinally extending recess on its bottom adapted to fit over the head of a supporting rail, the body on each side of said recess having depending ears, rail clamping members slidably mounted between said ears and adapted to engage beneath the head of the supporting rail and over the flange thereof, and means for holding said rail clamping members in position, the body being formed to support and clamp a rail to be broken.

5. A rail breaker comprising a body formed with a longitudinally extending recess on its under face adapted to embrace the head of a supporting rail, a U-shaped shim

disposable in said recess and over the head of the supporting rail, and means adjustably engaged with said body for engaging beneath the head of the supporting rail and holding the body in place thereon, the body having means for supporting and clamping a rail to be broken.

6. A rail breaker of the character described having a body formed with a longitudinally extending recess on its under face adapted to engage over the head of a rail, the under side of the body on each side of said recess being formed with downwardly depending, transversely perforated ears, rail clamping members disposable between said ears to extend beneath the head of the supporting rail and apertured to coincide with the apertures in said ears, and pins disposable through said apertures to lock the rail clamping members in place, the clamping members being formed on their inner faces to engage against the under face of the head of the rail against the web thereof and over the base flange of the rail, the body being formed with means for supporting and clamping the rail to be broken.

7. A breaker of the character described comprising a body formed with a longitudinally extending recess on its bottom adapted to engage over and embrace the head of a supporting rail, clamping members disposed on either side of said recess and engaged with said body and adapted to engage beneath the head of a supporting rail, the body being formed with opposed upwardly and then inwardly extending jaws adapted to overhang the base of a rail to be broken, these jaws having vertical screw-threaded apertures, and fillers angular in cross section adapted to be disposed beneath said overhanging jaws or to engage against the base of a rail and formed with apertures registering with the apertures in the jaws, and set screws engageable with the jaws and with said fillers and engageable with the base of the rail.

8. A breaker of the character described comprising a body formed with a longitudinally extending recess on its bottom adapted to engage over and embrace the head of a supporting rail, clamping members disposed on either side of said recess and engaged with said body and adapted to engage beneath the head of a supporting rail, the body being formed with opposed upwardly and then inwardly extending jaws adapted to overhang the base of a rail to be broken, these jaws having vertical screw-threaded apertures, fillers angular in cross section adapted to be disposed beneath said overhanging jaws to engage against the base of a rail and formed with apertures registering with the apertures in the jaws, the fillers being formed upon their free faces with

- longitudinally extending ribs and the jaws clamp and having an adjustable chisel on their under faces having longitudinally extending recesses to receive said ribs, and set screws engageable with the jaws and clamp, of a chisel holder, and means whereby said fillers and engageable with the base of the rail:
9. A breaker of the character described comprising a body formed with a longitudinally extending recess on its under face 10 adapted to embrace the head of a rail, clamping devices carried upon the body on each side of said recess and adapted to engage beneath the head of the rail and clamp against the web and over the flange thereof, the upper face of the body being formed with opposed inwardly extending overhanging jaws adapted to receive the base of the rail to be broken between them, fillers adapted to be disposed between the under faces 20 of said jaws and the base of the rail to be broken, a plate detachably engaged with the outer face of the body and having a flange at one end formed with an arcuately extending slot, and a chisel socket having a stud bolt passing through said slot whereby the chisel socket may be angularly adjusted.
10. The combination with a rail breaking clamp, of a chisel holder mounted upon the
11. The combination with a rail breaking clamp, of a chisel holder, and means whereby the chisel holder may be mounted at either end of the clamp, said chisel holder having an angularly adjustable chisel socket.
12. A rail breaking clamp including a body having means whereby it may be clamped upon a supporting rail and having opposed jaws to receive and clamp upon a rail to be broken, the lateral outer faces of the body being angular in form, an angular plate adapted to rest upon said angular outer faces, said plate being apertured and the body on each face having a screw-threaded bore to receive a cap screw adapted to extend through said plate, the plate at one end having a flange formed with an arcuate slot, and a chisel socket having a stud bolt passing through said slot, the stud bolt permitting the socket to be angularly adjusted.

In testimony whereof I hereunto affix my signature.

JUNIUS E. BUSBY.
